UNITED STATES PATENT OFFICE.

FRANK MISKOVSKY, OF LYNN, MASSACHUSETTS.

ENGINE-STARTER.

1,105,367.

Specification of Letters Patent. Patented July 28, 1914.

Application filed April 30, 1913. Serial No. 764,573.

To all whom it may concern:

Be it known that I, FRANK MISKOVSKY, a citizen of the United States, and a resident of Lynn, in the county of Essex and State 5 of Massachusetts, have invented a new and Improved Engine- Starter, of which the following is a full, clear, and exact description.

This invention relates to an apparatus 10 for starting automobiles or other engines, and it relates more particularly to a starting device of that type in which a single actuating means in the first part of its movement relatively connects the starting 15 shaft with the crank shaft of the engine, and during the remaining part of its movement causes the starting shaft to rotate the crank shaft sufficiently to enable the engine to start.

20 The invention has for its general object to improve and simplify the construction and operation of engine starting devices of the type disclosed in United States Letters Patent No. 1,047,103, granted to me December 25, 1912, whereby the apparatus will be more reliable and efficient, and comparatively inexpensive to manufacture and install.

Another object of the invention is the 30 provision of improved means for imparting longitudinal movement to the starting shaft to operatively connect the same with the engine crank shaft and thereafter to impart rotary movement to the starting shaft, said means serving to restore the parts to normal position when the operator releases the actuator, and provision is made whereby the starting shaft is automatically disconnected from the crank shaft in case 35 of backfire.

With these objects in view, and others as will appear as the description proceeds, the invention comprises various novel features of construction and arrangement of 40 parts which will be more fully described hereinafter and set forth with particularity in the claims appended hereto.

In the accompanying drawings, which 45 illustrate one embodiment of the invention, and wherein similar reference characters are employed to designate corresponding parts throughout the several views, Figure 1 is a view of the starting apparatus showing the same applied to an automobile; 50 Fig. 2 is an enlarged side view with the parts in normal position and with a por-

tion of the ratchet wheel broken away; Fig. 3 is a longitudinal section coincident with the axis of the starting shaft; Fig. 4 is a view similar to Fig. 2 with the parts 60 in a position occupied during the turning of the crank shaft of the engine; and Fig. 5 is a plan view of the starting device with the parts shown in Fig. 2.

Referring to the drawings, A designates 65 an ordinary automobile engine in which the shaft 1 is provided with a bevel gear 2 with which is adapted to mesh a bevel gear 3 of the starting device, such bevel gear 3 being normally out of mesh with the gear 2, 70 as shown in Fig. 5.

The starting apparatus B is in the nature of an attachment which can be applied to the frame of the automobile or to the engine A in such position that the gear 3 can 75 be thrown into and out of mesh with the gear 2. The attachment includes a bracket or other support 4 which is suitably mounted on the engine or automobile, and in this bracket or bearing 4 is a rotatable 80 and longitudinally movable starting shaft 5, to which the miter gear 3 is fastened. Keyed to the end of the shaft 5 opposite from the gear 3 is a ratchet wheel 6, and spanning this ratchet wheel are bifurcations 85 7 of a lever 8 which carries a pawl 9 that is adapted to engage the teeth 10 of the ratchet wheel 6, the parts being so disposed that when the lever 8 is moved in a clockwise direction, Figs. 1 and 2, as for 90 instance by the operating rod 11 connected with such lever, the ratchet wheel 6 and the shaft 5 will turn in the same direction.

As the gear 3 is normally out of mesh with the gear 2 it is necessary to impart a longitudinal movement to the shaft 5 to cause such gears to mesh, and this result is obtained by employing the initial part of the rotary movement of the shaft by the use of means 95 now to be described.

On the shaft 5 is a cam collar 12 that is provided in its periphery with a slot 13 having its ends *a* and *b* offset from each other in a plane transverse to the axis of rotation, and in this slot is arranged a roller 14 which 105 is carried by a plate 15 fastened to the bearing or bracket 4, and as a result, when the collar 12 is rotated, the roller 14 engaging in the cam slot 13 will cause the shaft 5 to move in a direction to mesh the gear 3 with 110 the gear 2. A device is employed to operatively connect the cam collar 12 with the

lever 8, so that the collar will rotate with the lever during the first part of the movement thereof. This device comprises a rib or catch block 16 carried by the hub 17 of the inner bifurcation 7 of the lever 8, and cooperating with this catch block 16 is a pivoted hook or latch 18 that has a shoulder 19 that is engaged by the catch block 16, as shown in Fig. 2. The hook or latch 18 is mounted on a pivot 20 carried by and projecting from the cam collar 12, and the latch has a heel 21 which is adapted to strike an abutment 22 formed by the plate 15. When the collar 12 has moved a sufficient distance to cause the shaft 5 to shift longitudinally for the engagement of the gear 3 with the gear 2 at this point the latch or hook 18 is raised, as shown in Fig. 4, so that continued movement of the lever 8 will cause the shaft 5 to rotate and in turn impart rotation to the crank shaft of the engine. The catch block or rib 16 extends into a circular groove 12^a in the collar 12, so as to provide a lost-motion connection between the lever 8 and such collar, the extremity 12^b of the groove 12^a being a shoulder with which the projecting end of the catch block 16 engages during the return or anti-clockwise movement of the lever, so that the cam collar 12 will be restored to normal position, whereby the shaft 5 will be retracted to position where the gear 3 will be disengaged from the gear 2.

In order to prevent backfiring of the engine from injuring the starting device, provision is made for causing the automatic disengagement of the gear 3 from the gear 2, and to accomplish this an arm 23 is carried by the cam collar 12, and on this arm is a pawl 24 which engages the ratchet wheel 6, so that when the latter is moved in the reverse direction by backfiring the arm 23 is carried with it so that the collar 12 will be caused to shift in a direction to move the shaft 5 longitudinally for releasing the gear 3 from the gear 2, the shifting of the shaft being effected by the roller 14 working in the cam groove 13 of the cam collar 12.

In starting the engine the handle 25 of the operating or pull rod 11 is pulled upwardly by the operator while seated in the automobile, and this movement of the rod causes the lever 8 to swing from the full to the dotted line position, Fig. 1. The initial position of the parts is shown in Fig. 2, and as the lever moves to the left the abutment 16 by engaging with the hook or latch causes the cam collar 12 to move with the lever 8 as a unitary device until the shaft 5 is shifted longitudinally to engage the gear 3 with the gear 2. At this point the heel 21 strikes the abutment 22 and releases the hook 18 from the abutment 16, so that continued movement of the lever 8 in the same direction as before will result in only a rotary movement of the

shaft 5, whereby the latter rotates the crank shaft. As soon as the engine has started the crank shaft will rotate the starter shaft 5 and cause the ratchet wheel 6 to slip past the pawls 9 and 24. The operator now returns the pull rod 11 to normal position, so that the shaft 5 will be shifted longitudinally in a direction to release the gear 3 from the gear 2.

From the foregoing description taken in connection with the accompanying drawings, the advantages of the method of operation and of the apparatus shown will be readily understood by those skilled in the art to which the invention appertains, and while I have described the apparatus which I now consider to be the best embodiment thereof, I desire to have it understood that the apparatus shown is merely illustrative, and that such changes may be made when desired as are within the scope of the appended claims.

Having thus described my invention, I claim as new and desire to secure by Letters Patent:

1. In an engine starter, the combination of an engine shaft, a starting shaft normally disengaged from the engine shaft, an actuator, a member operatively connected with the starting shaft to engage and disengage the two shafts and movable with the actuator during the first part of the movement thereof, a fixed member engaging the movable member whereby movement of the latter with the actuator causes said member to move in a direction to engage the starting shaft with the engine shaft, a pivoted device mounted on the movable member, and means on the actuator and with which the device initially engages for moving the said movable member with the actuator, and means for releasing the device from the said means to permit the actuator to rotate the starting shaft after the latter has been shifted by the first mentioned member into engagement with the engine shaft.

2. An engine starter comprising a rotatable and longitudinally movable shaft, an actuator, a ratchet and pawl mechanism between the actuator and shaft, a cam collar on the shaft, means engaging the collar to produce longitudinal movement of the said shaft by the rotation of the collar, a pivoted latch on the collar, means carried by the ratchet and pawl mechanism with which the latch engages to cause the collar to move with the said mechanism, and a fixed device for releasing the latch when the collar has finished moving the said shaft longitudinally.

3. An engine starter comprising a rotatable and longitudinally movable shaft, an actuator, a ratchet and pawl mechanism between the actuator and shaft, a cam collar on the shaft, means engaging the collar to

produce longitudinal movement of the said shaft by the rotation of the collar, a pivoted latch on the collar, means carried by the ratchet and pawl mechanism with which the latch engages to cause the collar to move with the said mechanism, a fixed device for releasing the latch when the collar has finished moving the said shaft longitudinally, and an abutment on the collar with which 10 the said means engages to restore the collar to normal position on the return movement of the actuator.

4. A starting device for engines, comprising a longitudinally and rotatably movable shaft, a collar thereon having a cam groove, means engaging the groove for imparting longitudinal movement to the shaft by the rotation of the collar, an operating lever operatively connected with the shaft to turn 15 the same, a member carried by the lever, a pivoted hook-shaped latch on the collar arranged to engage the said member for connecting the collar and lever together for simultaneous movement, and a fixed abutment disposed to engage the latch to release the same from said member when the collar has finished moving the shaft longitudinally. 20

5. A starting device for engines, comprising a longitudinally and rotatably movable shaft, a collar thereon having a cam groove, means engaging the groove for imparting longitudinal movement to the shaft by the rotation of the collar, an operating lever operatively connected with the shaft to turn 25 the same, a member carried by the lever, a pivoted hook-shaped latch on the collar arranged to engage the said member for connecting the collar and lever together for simultaneous movement, and a fixed abutment disposed to engage the latch to release the same from said member when the collar has finished moving the shaft longitudinally, 30

40

said collar having a groove into which one end of the said member extends for engagement with one end of the groove during the 45 return movement of the lever for restoring the collar to normal position.

6. A starting device for engines, comprising a longitudinally movable and rotatable shaft, a mechanism for rotating the 50 shaft, a member carried by the mechanism, a collar on the shaft for imparting longitudinal movement thereto, a hook-shaped latch pivoted on the collar and having one end arranged to engage the said member to 55 connect the collar with the mechanism for movement with the latter, and a fixed abutment for engaging the opposite end of the latch to release the same from the said member when the collar has finished mov- 60 ing the shaft longitudinally.

7. A starting device for engines comprising a longitudinally movable and rotatable shaft, a collar thereon having a cam groove, a stationary device engaging in the groove 65 for imparting longitudinal movement to the collar by the rotation of the latter, an actuating mechanism, a member on the mechanism and movable therewith, and a pivoted hook-shaped latch mounted on the collar to 70 engage the said member for connecting the collar with the mechanism to move therewith, said latch having a heel arranged to strike the said stationary device for releasing the latch from the said member when 75 the collar has finished moving the shaft longitudinally.

In testimony whereof I have signed my name to this specification in the presence of two subscribing witnesses.
